GRAIN CAR DOOR IMPLEMENT

Cornell Flagstad, Minneapolis, Minn.

Application April 22, 1944, Serial No. 532,296

7 Claims. (Cl. 254—113)

1

This invention relates generally to improvements in grain car doors and more particularly to means for opening or raising the doors of the cars used by railroads for transporting grain.

Cars for this purpose have side openings for loading and unloading the grain and it is, of course, necessary to close or board up these openings during transport. Doors are accordingly provided for the openings and these doors are arranged in superimposed edge to edge relation crosswise of the opening and inwardly of the side parts thereof. In practice the doors are opened and removed one at a time, starting with the one uppermost, by urging the doors upwardly so that the grain may run out beneath. When the outward pressure of the grain against the doors is thus relieved the doors may be removed and put aside until needed again.

Due to the pressure of the grain the raising of the doors requires considerable force and heretofore this has been accomplished by various tools, all of which were makeshift to some extent and most of which caused damage to the car and doors such as to render the latter soon unfit for further use.

It is the primary object of my invention therefore to provide an implement of simple and durable nature for raising grain car doors and which may be readily and conveniently used for the purpose, will provide adequate force and leverage for proper operation, and which is very rapid in operation. Another object is to provide an implement which, used with grain car doors having suitable means for accommodating it, will not only make the raising of the doors very easy but will cause no damage whatever to cars or doors.

These and other more detailed and specific objects will be disclosed in the course of the following specification, reference being had to the accompanying drawings, in which—

Fig. 1 is a fragmentary outside elevation of a grain car doorway provided with doors adapted to the use of my implement.

Fig. 2 is an enlarged vertical section along the line 2—2 in Fig. 1 showing two tools in use upon the doors.

Fig. 3 is an enlarged fragmentary view of the implement of Fig. 2, showing connecting linkage and parts thereof.

Fig. 4 is a composite view, showing fragmentary front and side elevations of a slightly modified form of implement.

The present application is a continuation-in-part of my copending application Serial No. 358,964, filed September 30, 1940, which became

2

abandoned May 28, 1944, to which attention is invited for comparative purposes.

Referring now more particularly and by reference characters to the drawings, A designates 5 one of the two upright side posts which define the lateral margins of a grain car doorway, B the car floor and C the doors by which the doorway is closed when the car is filled with grain.

The doors C are of such length as to more 10 than span the doorway, extending at their ends against inner surfaces of the door posts A as seen in dotted lines in Fig. 1, and the doors are arranged on edge one above the other to close the doorway to any height desired. As here shown 15 the doors are three in number but any number may of course be used as required. In practice the doors may be held to the posts by lightly nailing from the inside, or by other suitable means which will permit the doors to be easily 20 pried free by a suitable tool and then moved upwardly one at a time to permit the grain to run out beneath. The pressure of the grain against the inner sides of the doors will, of course, normally assist in holding them in place.

25 The doors may be constructed in any suitable manner and are herein shown as of two ply thickness, formed of oppositely laid boards and are provided adjacent each end with two upright, transversely spaced cleats C'.

30 In accordance with my present invention I provide the doors C with means at each end for accommodating a raising implement, one of which will be used at each end of the doors in practice. Such means for accommodating the 35 implements comprises bracket members of two forms, one a hook 10 and the other a rest 11. One each of these members is mounted at each end of the doors, for which purposes the members are provided with apertured base lugs designated generally at 12 adapted to be screwed, nailed or otherwise secured to the doors, preferably in the upright channel-like spaces between the cleats C'. The hooks 10 are located substantially midway of the vertical width of the doors 40 whereas the rests 11 are mounted near the upper edges. The hooks 10 have downwardly opening recesses 13 while the rests have upwardly opening recesses 14.

Referring particularly to Fig. 2 I show therein 50 a pair of the implements, designated generally at 15 and 16, one operating upon the uppermost door C while the other is reversed and arranged in position for raising the lowermost door. Ordinarily the implements are not used in pairs at each end of the doors and this showing is made

for convenience only. The implements 15 and 16 thus shown are of course identical in construction.

Implement 15 comprises a handle or handle member 17 made up of spaced, longitudinally extending side bars 18 and 19 between which at one end is secured a wooden filler 20 to form a handy gripping end. The opposite or operating end 21 of the handle is provided with a pin 22 which is riveted crosswise between the rounded extremities of the side bars 18 and 19 and holds them in properly spaced relation. The implement further comprises a leg or arm member 23 which has a bifurcated operating end portion 24 provided with a cross pin 25 similar to pin 22. The other end of the leg member 23 has an offset head or knuckle 26 and pivoted thereto at 27 and 28 respectively are long and short links 29 and 30. The long links 29 extend between the side bars 18 and 19 toward the gripping end of the handle and are longitudinally slotted at 31 to engage a pin 32 secured crosswise between said bars. The short links 30 extend in a generally opposite direction and are pivotally attached at their other ends to a pivot pin 33.

The links 29 and 30 form a floating or shifting pivot connection between the leg member 23 and handle 17 and permit the leg member to swing freely from a position extending almost straight outwardly or endwise from the handle, as seen in the lower tool in Fig. 2, to a folded or carrying position in which the leg member lies almost flat against and toward the gripping end of the handle. The leg member is normally urged toward either of these positions by an expansion coil spring 34 which is coiled around an arm 35, pivoted at one end at 36 to the head 26 eccentric to both of the pivots 27 and 28, and at its other end longitudinally slotted at 37 (Fig. 3) to play over a pin 38 secured between the long links 29. The spring is braced between an enlarged end 39 of the arm 35 and the pin 38 and normally tends to urge point 36 to one side or the other of the link pivot 28 and thus swing the leg member to either position described. The spring positioning of the leg member thus prevents it from swinging about loosely and possibly injuring the user.

In use the implement is first engaged between the uppermost door and the one next beneath. For this purpose the leg member 23 is swung outwardly from normal carrying or folded position to extend endwise beyond the operating end 21 of the handle 17 and the respective pins 25 and 22 will now just nicely engage between the hook 10 on the upper door and the rest 11 on the one beneath, the handle of the implement hanging downwardly and being supported by the rest 11. Now as the handle 17 is grasped and swung upwardly, as shown in Fig. 2, an upward thrust will be exerted on the hook 10 on the upper door, urging the door upwardly, and this action may continue until the door is thrown upwardly and inwardly over the grain in the car.

What occurs is effectively the spreading of the operating ends 21 and 24 of the implement handle 17 and leg member 23, and since these ends are braced by the pins 22 and 25 between the rest 11 and hook 10, respectively, the upper door necessarily must move upward with respect to the lower. In the operation of swinging the handle 17 upwardly the leg member 23 first oscillates about a center located substantially at the same distance as the pin 33 from the end of the handle

carrying pin 22, thus providing the maximum advantage and leverage in starting the door upward. As the handle approaches a more horizontal position, however, the links 29 and 30 swing outward and the effective leverage between the handle 17 and leg member 23 decreases, as the load decreases, while, at the same time the effective included angle between the handle and leg member will increase. The latter result permits the operating ends 21 and 24 to be spread to a maximum distance apart to raise the door far enough to cast it inward upon the grain.

The action may be repeated until all but the lowermost door is removed whereupon the implement is reversed and the pin 22 engaged beneath the hook 10 on this door, while the leg member 23 is turned downward and braced against the car floor B. This is the position assumed by the implement 16 in Fig. 2, and it will be apparent that downward swinging movement of the handle 17 will now urge the lowermost door upwardly with respect to the car floor with the same effectiveness as the other doors are raised.

As shown in Fig. 4 I may dispense with the floating pivot for the leg member of the implement where the maximum in simplicity is required, or where a reduction in the effective lift on the doors may be endured. Here the leg member is designated at 23^a and has two diverging side members 40 and 41 which enter between the side bars 18 and 19 of the handle 17 and are pivoted upon the pivot pin 33. An expansion coil spring 42 is coiled on pin 33 between the pivoted ends of the side members 40 and 41 and urges them outward into frictional or braking engagement with inner sides of the bars 18 and 19. Thus the leg member 23^a will be prevented from flopping freely about and pinching or striking the user. Otherwise the construction of this implement is identical to that described hereinbefore, the handle 17 having a cross pin 22 and the leg member a cross pin 25 as clearly shown.

It is understood that suitable modification may be made in the structures disclosed, provided that such modifications lie within the spirit and scope of the appended claims. Having now, therefore, fully disclosed my invention, what I claim as new and desire to secure by Letters Patent is:

1. An implement for raising grain car doors, comprising in combination, a handle having an operating end, a pin in said operating end, a leg member, means pivotally connecting the leg member to the handle, the said leg member having an operating end swingable about said connection with respect to the operating end of the handle and said operating end of the leg member also having a pin, each door having a hook member in which one of the said pins may be releasably engaged, and rest means on each door for engagement by the other pin whereby spreading movements of the operating ends of the handle and leg members carrying said pins will urge the doors apart.

2. An implement for raising grain car doors each having a rest member and a hook member mounted in vertically spaced relation, comprising in combination, a handle having an operating end, a cross pin on said operating end, a leg member having an operating end, means forming a pivotal connection between the other end of the leg member and the handle and permitting swinging and spreading movements of the operating end of the leg member toward and away

from the operating end of the handle in response to manipulation of the handle, a cross pin on the operating end of the leg member, the said cross pins being releasably engageable with a hook member on one door and a rest member on the door next beneath whereby the spreading of the operating ends of the handle and leg member will urge one door upwardly with respect to the other, and the said leg member being also operative to brace against the car floor with the pin in the operating end of the handle engaging the hook member on the lower door for raising the lower door with respect to said floor.

3. An implement for raising grain car doors each having a rest member and a hook member mounted in vertically spaced relation, comprising in combination, a handle having an operating end, a cross pin in said operating end, a leg member having an operating end, means forming a movable connection between the other end of the leg member and the handle permitting swinging and spreading movements of the respective operating ends of the handle and leg member in response to manipulation of the handle, a cross pin in the operating end of the leg member, the said cross pins being releasably engageable with the hook and rest members in the doors for exerting vertical spreading movements between the doors, and the said connection between the leg member and the handle being spring set to hold the leg member in adjusted positions with respect to the handle.

4. An implement for raising grain car doors each having a rest member and a hook member mounted in vertically spaced relation, comprising in combination, a handle having an operating end, a cross pin in said operating end, a leg member having an operating end, means forming a swingable connection between the other end of the leg member and the handle permitting relative swinging and spreading movements of the respective operating ends of the handle and leg member in response to manipulation of the handle, a cross pin in the operating end of the leg member, the said cross pins being releasably engageable with the hook and rest members in the doors for exerting vertical spreading movements between the doors and the said connection between the leg member, and the handle including links pivotally connected to the leg member and handle and movable with respect to the latter forming a shifting pivot connection between the leg member and handle.

5. An implement for raising grain car doors each having a rest member and a hook member mounted in vertically spaced relation, comprising in combination, a handle having an operating end, a pin in said operating end, a leg member having an operating end and a pin therein and said member having a pivotal connection between

its other end and the handle and permitting swinging and spreading movements of its operating end toward and away from the operating end of the handle in response to manipulation of the handle, the said pins being releasably engageable with the hook and rest members in the doors for exerting vertical spreading movements between the doors, the said leg member including a bifurcated portion, and spring means for urging said bifurcated portion of the leg member into frictional engagement with the handle to hold the leg member in adjusted positions with respect to the handle.

6. An implement for lifting grain car doors of the type which are arranged edgewise one above the other to close the grain car doorway from the car floor upwardly, comprising a handle member, a leg member, means swingably connecting the handle and leg members whereby corresponding ends thereof may be swung toward and spread away from each other, each of the said doors having a rest member and a hook member secured thereto in vertically spaced relation, and means on the said ends of the handle and leg member for engaging the rest member on one door and the hook member on the next door next above whereby manipulation of the handle to cause spreading movements of the handle and leg member will pry the upper door upward.

7. An implement for raising grain car doors of the type which are arranged edgewise one above the other upon the floor of the car, said doors each having a rest member and a hook member secured thereto, a handle member having an end adapted to rest upon the rest member of any selected door, and a leg member connected to the handle member and adapted to project upwardly therefrom and engage at its upper end with the hook member on the door next above whereby lifting movements of the handle will force the door engaged by the leg member in an upward direction.
